FOOD WARMER

Robert G. Wilson, 643 E. Faris Road, Greenville, S.C.

Filed Aug. 3, 1964, Ser. No. 81,140

Term of patent 14 years

(Cl. D81—10)

Fig. 1.

Fig. 2.

The supports, shown fragmentarily in broken lines, are included for illustrative purposes only.

I claim:

The ornamental design for a food warmer, substantially as shown and described.
